THUMB-ORIENTED FOOD TRAY

Merton J. Alexander, 173 Highland Place,
Monrovia, Calif. 91016

Filed Oct. 3, 1973, Ser. No. 402,976

Term of patent 14 years

Int. Cl. D7—99

U.S. Cl. D7—38

FIG. 1

FIG. 2

FIG. 1 is a perspective view of a thumb-oriented food tray showing my new design; and

FIG. 2 is a sectional elevation taken along line 2—2 of FIG. 1.

The bottom is substantially plain and unornamented.

I claim:

The ornamental design for a thumb-oriented food tray, as shown and described.
